UNITED STATES PATENT OFFICE.

LUCINDA VINING, OF GAINESVILLE, TEXAS.

COVERING-MACHINE.

SPECIFICATION forming part of Letters Patent No. 628,049, dated July 4, 1899.

Application filed January 27, 1898. Serial No. 668,219. (No model.)

To all whom it may concern:

Be it known that I, LUCINDA VINING, a citizen of the United States, residing at Gainesville, in the county of Cooke and State of Texas, have invented certain new and useful Improvements in Rag-Joiners; and I do hereby declare the following to be a full, clear, and exact description of the invention, such as will enable others skilled in the art to which it appertains to make and use the same.

My present invention relates to a novel machine for joining fabric strips designed to be used as filling in rag carpets or the like.

The machine is designed to wind a fine thread or other continuous strand around the strips longitudinally and embodies improvements for properly feeding the strips, winding the continuous strand around them in a manner to insure their connection without the necessity of tacking them together as by sewing in the ordinary manner.

The invention consists, further, in certain novel details of construction and in the arrangement of parts hereinafter described and claimed.

Referring to the drawings, Figure 1 is a top plan view of the apparatus complete. Fig. 2 is a side elevation thereof. Fig. 3 is a similar view of the opposite side; and Fig. 4 is a detail view of two strips of fabric, showing the manner in which they are connected. Fig. 5 is a detail vertical section through the bobbin-tube, showing the manner of supporting the bobbin.

Referring to the numerals on the drawings, 1 indicates the bed or base plate, at one end of which is located a bearing-frame 2, carrying at its top a pair of journal-boxes 3, in which is journaled a power-shaft 4, provided with a crank or other power-transmitting device 5. Keyed or otherwise secured upon the shaft 4 is a belt-wheel 6, from one side of which extends a comparatively small belt-pulley 7.

8 indicates a feed-roll extending longitudinally along one side of the base-plate at the desired elevation and supported by bearing-brackets 9. The feed-roll is designed to be rotated by a feed-belt 10, passing around the pulley 7 and the roll, a pair of idlers 11 being suitably mounted between the base-plate and a horizontal bracket 12, extending from one

of the brackets 9 to properly direct the belt to accommodate the right-angular disposition of roll-and-power shaft. 55

13 indicates a belt-tightener composed of an oscillating arm 14, pivoted, as indicated at 15, upon the plate 1, and an idle pulley 16, carried at the free end of the arm and engaging one strand of the feed-belt. 60

17 indicates a corrugated friction-roller in yielding contact with the feed-roll and journaled at the upper end of a standard 18, extending from one end of a slide 19, laterally movable with respect to the plate in suitable ways 20, a spring 21, secured at its opposite ends to the slide and base-plate, serving to constantly urge the friction-roller toward the feed-roll. 65

The mechanism thus far described comprehends the means for feeding the fabric at the desired speed, and I shall now proceed to a description of the mechanism which winds the strand around the fabric strip to effect the connection. 70

22 indicates a fixed standard rising from the side of the bed-plate directly opposite the standard 18, and from its top extends horizontally across the frame a guide in the form of a smooth stout wire or rod 23, supported 80 fixedly at one end only, located axially within what may be termed a "bobbin-tube" 24, consisting of two concentric tubes 25 and 26, the inner of which may be made of some light material—as, for instance, pasteboard or the like—while the outer tube is preferably of metal. The bobbin-tube is open at both ends and revolvably mounted in suitable bearings 27, carried by uprights 28, and is revolved at a comparatively high rate of speed by a belt 90 passing around the tube and the belt-wheel 6. The guide 23 terminates near the opposite side of the machine, so that there is no obstruction to the passage of the joined strips therefrom. 95

29 indicates a bobbin of any ordinary or approved construction mounted at the end of the tube adjacent to the standard 22 by passing one end of an angular or L-shaped rod or wire 30 between the tubes 25 and 26, where it is rigidly held, the outer bent end of said rod serving as the shaft or spindle of the bobbin. 100

Any suitable tension device 31 may be applied to keep the strand as it comes from the

bobbin at the proper tension; but I consider the spring-loop illustrated preferable for this purpose.

In operation the crank 5 is turned and the 5 end of a fabric strip 32 is fed upon the rod 23 in the direction of the bobbin. The end of the strand 33 wound upon the bobbin is now passed once or twice around the strip and rod. The strip is then fed forward by 10 hand until its end passes through the bobbin-tube and is engaged between the feed-roll and the friction-roller, the rotation of the bobbin with the tube having in the meantime wound the strand in a more or less gradual spiral 15 around the strip. The feed will now be automatic, as the friction-roller will maintain an operative relation between the strip and the feed-roll. The operator now laps one end of a second strip over the rear end of the first 20 strip, and as the lap or joint reaches the bobbin the slide 19 is moved against the resistance of the spring to throw the friction-roll out of contact with the feed-roll. This will interrupt the feed of the strips and will cause 25 the strand to be wound closely around the lap or joint, after which operation the slide is released and the feed is resumed until the next lap or joint is reached. If desired, wire baskets or other receptacles may be hung upon 30 the frame to receive the strip as it passes off the free end of the guide. Thus it will be seen that I have produced a novel machine for connecting or joining fabric or other strips; but while the present embodiment of the in- 35 vention appears at this time to be preferable

many minor changes in the details of construction may be resorted to without departing from the nature or spirit of the invention.

Having thus described my invention, what I claim to be new, and desire to secure by Letters Patent, is—

1. The combination with a bobbin-tube and means for rotating the same, of a guide-rod supported at one end and extending into the tube, a feed-roll located at right angles to the bobbin-tube and beyond one end thereof, means for actuating the feed-roll, a friction-wheel yieldingly urged against the feed-roll, and a bobbin carried by the bobbin-tube and designed to revolve around a strip fed there- 40 through, substantially as specified.

2. The combination with a bobbin-tube and a bobbin carried thereby, of a guide-rod extending into the bobbin-tube and designed to support the strips, a feed-roll located at right 45 angles to the bobbin-tube, a spring-actuated slide, a friction-roll carried by the slide in yielding engagement with the feed-roll, a power-shaft, belt-pulleys carried thereby, and means for actuating said shafts, and belts 50 passing over the belt-pulleys and around the bobbin-tube and feed-roll respectively, and means for taking up the slack in one of the belts, substantially as specified.

In testimony whereof I affix my signature 55 in presence of two witnesses.

LUCINDA VINING.
